UNITED STATES PATENT OFFICE.

FREDERICK M. MOULTON, OF PINE ISLAND, MINNESOTA.

BRAKE.

1,151,374.

Specification of Letters Patent.

Patented Aug. 24, 1915.

Application filed September 26, 1914. Serial No. 863,706.

To all whom it may concern:

Be it known that I, FREDERICK M. MOULTON, a citizen of the United States, residing at Pine Island, in the county of Goodhue 5 and State of Minnesota, have invented certain new and useful Improvements in Brakes; and I do hereby declare the following to be a full, clear, and exact description of the invention, such as will enable others 10 skilled in the art to which it appertains to make and use the same.

My invention relates to improvements in brakes of the type adapted for use in connection with traveling carriers that are 15 slidable upon cables and has for its primary object to provide a novelly constructed brake attachment that may be readily and easily attached to carriers and will operate to retard the movement of the carriers or 20 hold the carriers against movement altogether, when desired.

Another object is to improve brakes of the character described so as to render them more practical, reliable and efficient in operation and inexpensive to manufacture. 25

The above and additional objects are accomplished by such means as are illustrated in the accompanying drawings, described in the following specification and then more 30 particularly pointed out in the claims.

With reference to the drawings, wherein I have illustrated the preferred embodiment of my invention as it is reduced to practice, and throughout the several views 35 of which similar reference numerals designate corresponding parts, Figure 1 is a fragmentary side elevation of a part of a carrier showing my improved brake attachment thereon and in operative position also in 40 inoperative position in dotted lines, Fig. 2 is a sectional view taken through a part of the carrier and showing the brake lever and shoe in top plan, and Fig. 3 is a detail side elevation of the hook for supporting the 45 lever when the brake is not in use.

Referring to the drawings by characters of reference, the numeral 1 designates a suspension cable for a carrier designated 2 as an entirety. The carrier 2 is shown only in 50 part and is suspended by a pulley or pulleys 3. The pulley 3 is mounted upon the cable 1 and connected with the pulley 3 is a depending receptacle supporting arm 4. In the type of carrier which is illustrated in 55 the drawing in part, the carrier consists of two upright members 4 and two pulleys 3.

The upright members 4 are connected by a horizontal cross or connecting bar 5 that is shown in part in the drawings.

My improved brake attachment comprises 60 a brake lever designated 6 as an entirety that is pivoted intermediate its ends as at 7 to a clamping member 8 on one side of said clamping member. The clamping member 8 comprises a plate 9 that is pivoted to the 65 lever 6 and a detachable plate 10 that is secured to the plate 9 by means of bolts 11 which have nuts 12 turned on their threaded terminals.

The clamping member 8 is designed to engage and clamp upon the rod 4 at a point adjacent the upper end of said rod. The lever 6 is bowed as at 13 at a point between one end and the pivot point 7 thereof and at the free end of said bowed portion 13 is 75 secured a brake shoe 14 that is approximately U-shaped in cross section and engages the cable 1. The curving of this lever 16 brings the free end of the curved portion into a position so that the shoe 14 will be 80 brought to bear against the cable 1.

A helical retractile spring 15 is secured to one end as at 16 to the rod or bar 5 and at its other end to an eye 17 carried on the bowed portion 13 of the lever 6. This 85 spring 15 normally holds the brake shoe 14 into braking position. A hook designated 18 is detachably connected with the bar 5 and is designed to engage one end of the lever 6, said end being notched as at 19 so 90 as to receive the lower part of the hook and securely hold itself in position. The bowed portion 13 is offset so as to not interfere with the spring 15 or adjacent parts of the carrier.

In operation when it is desired to release the brake from position as shown in Fig. 1, that is, braking position, the lever 6 is moved upwardly and the notched end 19 thereof placed within the hook 18. It will be readily 100 seen that the carrier will be held against movement if desired by the use of my improved brake.

In practice, I have found that the form of my invention, illustrated in the drawings 105 and referred to in the above description, as the preferred embodiment, is the most efficient and practical; yet realizing that the conditions concurrent with the adoption of my device will necessarily vary, I desire to 110 emphasize the fact that various minor changes in details of construction, propor-

tion and arrangement of parts may be resorted to, when required, without sacrificing any of the advantages of my invention as set forth.

5 What is claimed is:—

1. In a brake the combination with a cable, and a pulley or wheel arranged to run on the cable, of a carrier suspended from the pulley or wheel and a brake lever pivoted at a point intermediate of its ends to the carrier at a point below the axis of the pulley or wheel and provided at one end with a shoe arranged to engage the under side of the cable below the pulley or wheel 10 to coöperate therewith in clamping the said cable.
2. In a brake the combination with a cable, and a pulley or wheel arranged to run on the cable, of a carrier including a supporting bar depending from the pulley 15
- 20

or wheel and a horizontal bar connected with the supporting bar, a clamp secured to the supporting bar below the horizontal bar and provided with a pivot located below the axis of the pulley or wheel, a brake lever fulcrumed at an intermediate point on the said pivot and provided at one end with means for engaging the cable at a point below the pulley or wheel, a spring connected with the brake lever for urging the same against the cable and means carried by the horizontal bar and arranged to engage the brake lever for holding the same away from the cable. 25

In testimony whereof I affix my signature in presence of two witnesses.

FRED. M. MOULTON.
